UNITED STATES PATENT OFFICE.

BENJAMIN F. PERRY, OF MONTREAL, QUEBEC, CANADA.

DOOR CHECK AND LATCH MECHANISM.

Application filed December 27, 1924. Serial No. 758,461.

To all whom it may concern:

Be it known that I, BENJAMIN F. PERRY, a subject of the King of Great Britain, residing at the city of Montreal, in the Province of Quebec, Dominion of Canada, have invented new and useful Improvements in Door Checks and Latch Mechanism, of which the following is a specification.

This invention relates to door checks and latch mechanism adapted to co-operate as hereinafter set forth and to novel features and improvements to the device covered by United States Patent No. 1,049,529 dated January 7th, 1913.

The object of the invention is to provide a door check of simple and durable construction adapted to engage the floor automatically in any position of the door, actuated by the latch and operating therewith.

A further object is to provide means to lock and unlock the latch and door check.

A further object is to provide a device that is reversible and is applicable to either mortise locks or rim locks in any position on the door.

A further object is to provide means to withhold the door check from operating without affecting the operation of the latch.

Reference is made to the accompanying drawings in which:—

Fig. 1 is a side elevation of the device partly in section.

Fig. 2 is an enlarged vertical section of a lock casing with the special latch mechanism.

Fig. 3 is a vertical cross section on the line 3—3 of Fig. 2.

Fig. 4 is a cross section on the line 4—4 of Fig. 2.

Fig. 5 is an enlarged sectional view of the latch mechanism.

Fig. 6 is a side view of the night lock mechanism.

Fig. 7 shows the details of the foot piece.

Fig. 8 shows the rod adapted to a rim lock.

Fig. 9 shows the latch bolt key release.

Fig. 10 is a plan view of the same.

Fig. 11 shows the stop for check rod.

Fig. 12 shows a key for latch bolt release.

Referring to the drawings, the door 1, is provided with a casing 10, of the usual form, containing in its lower part the well known lock mechanism 11.

In place of the common form of latch mechanism with its centrally operated bolt,

a short bolt 2, is employed, narrowed at its inner end 20, in which the vertical bore 21, is adapted to hook on the vertical lug 31, of the latch bar 3. 60

The projecting end of the bolt 2, is bevelled in the usual way.

The connection between the bolt 2, and the latch bar 3, provides a ready means of reversing the position of the bolt 2, when necessary. 65

The latch bar 3, is provided with a pin 33, at its other end and a coil spring 32, bearing on the casing wall 102 or a projection therefrom, and surrounding the pin 33, 70 normally presses the bar 3, and bolt 2, to the extended position as shown in Fig. 2.

The latch bar 3, has a rack 34, on its lower edge.

A slot 35, inclined at 45° towards the 75 bolt plate 101, enters the latch bar 3, from above.

The parallel edges of the slot 35, provide guides 350, for a reciprocating block 4, 80 which travels in the slot 35.

The block 4, has a square bore 41, to receive the pin end 420, of the pin 42.

The latch bar is preferably strengthened by a rib on one side adjacent the rack.

A stop 105, projecting from the wall 103, of the casing 10, prevents the block 4, from 85 leaving the slot 35.

The latch shaft 5, provided with the usual lengthening adjustments and handles, is journaled in the casing below the latch bar 90 3, and is squared to receive the pinion or pawl 6, meshing with the rack 34, of the latch bar 3.

In order to provide a night lock for the latch the shaft is made in two parts 51 and 95 52 with rotating connection 50.

The inner part 51, carries the pinion 6, at its end.

The outer part 52, carries a sliding pinion 61, adapted to be moved away from the teeth 100 of the rack 34, to mesh with the teeth of a stop 106, projecting from the casing wall 103.

A spring 62, normally presses the movable pinion 61, to mesh with the rack 34. 105

A wedge fork 64, controlled by a rocking lever 65, and two press pins 66 and 661 forces the movable pinion 61, away from the main pinion 6, into the stop 106.

The press pins 66 and 661 are operated 110 by the finger in countersunk holes in the lock plate 101.

A spring 107, holds the wedge fork in either position by means of the projections 640.

5 A guide 108, on the wall 103, holds the fork 64, in sliding position.

The rod 7, guided in brackets 70, close to the surface of the door 1, extends towards the floor.

10 Its upper end is slotted at 71, to receive the flattened end 421, of the pin 42, whereby it is connected with the latch mechanism.

The pin 42, is squared and reciprocates in a slot 14 through the casing wall, the door and the escutcheon.

15 The sides of the slot in the casing wall are preferably thickened to provide a guide way for the pin.

The lower end of the rod 7, is secured to a foot piece 74, sliding in a guide 73. The 20 foot piece 74, may be offset in order to allow clearance from the saddle of the door.

The foot piece 74, is provided with a rubber tip 75, preferably of semi-circular cross section and having a flat end bearing on the 25 floor.

When the device is employed with a rim lock the rod 7, is offset at 72, as shown in Fig. 8.

In order to permit the latch to be opened 30 when the night lock is set I provide a short band of flexible metal 22 secured to the latch bolt 2 at one end, passing through a slot 23 in the casing wall 103 and having a key grip 25 at the other end.

35 A roller 24 may be provided at the edge of the slot 23.

A key hole 26 and ferrule is provided for the insertion of the key 8 from the outer side of the door.

40 The key 8 is preferably provided with a hinged cross bar 80 in order to give a firmer grip, while its point 81 is adapted to catch the key grip.

The ordinary operation of the device is as 45 follows:—The tension of the spring 32, on the latch bar 3, forces it with the latch bolt 2, to the position shown in Fig. 2.

The block 4, sliding in the slot 35, is near its lowest position when the latch bar is 50 fully extended.

The rod 7, is then depressed and the rubber tip 75, of the foot piece 74, is pressing on the floor, holding the door firmly in any set position.

55 When the handles are rotated the pinion operates the rack and moves the latch bolt and latch bar backwards against the tension of the spring. At the same time the block moves upwardly in the slot and the pin 60 raises the rod and frees the rubber tip from the floor surface, permitting the door to swing freely on its hinges.

The stop 422 may be slid under the pin 42 whereby the rod 7 is prevented from descending and the door check is held out of

contact with the floor, while allowing the latch to operate.

By making the slot 35, deeper than is required for the normal floor level the block 4, the pin 42, and the rod 7 can move downwards, and foot piece 74, may be enabled to descend sufficiently to reach the floor even when it is sunk to a lower level or is uneven.

The form of the device as above described is suitable for interior doors but when applied to an outside door and it is desirable to lock the latch, the night lock mechanism must be added. With this mechanism the outer handle is locked when the upper press pin is pressed inwards and the latch bolt 80 can only be withdrawn and released by means of the key.

What I claim is:—

1. In a door check the combination of a latch operating mechanism with means to 85 raise and lower a door check and means to hold the door check out of contact with the floor without affecting the normal latch operation.

2. In a device of the class described the 90 combination of a casing, a latch mechanism comprising a reversible latch bolt, a latch bar coupled thereto having a toothed rack on its edge, a coil spring, and a handle controlled pinion, with an inclined slot in the 95 latch bar, a block reciprocating therein, a pin connecting the block with a door check rod, adapted to raise the rod when the latch bolt is withdrawn.

3. In a device of the class described the 100 combination of a casing, a latch mechanism comprising a reversible latch bolt, a latch bar coupled thereto having a toothed rack on its edge, a coil spring, and a handle controlled pinion, with an inclined slot in the 105 latch bar, a block reciprocating therein, a pin connecting the block with a door check rod, adapted to raise the rod when the latch bolt is withdrawn, with means to lock the check in a free position without affecting the normal latch operation.

4. In a device of the class specified the 110 combination of a door check adapted to hold the door in any position having a latch operating mechanism adapted to operate the door check with a latch locking mechanism adapted to lock the latch on one side of the door.

5. In a device of the class specified the 120 combination of a door check with a latch operating mechanism adapted to operate the door check and a latch locking mechanism adapted to lock the latch on one side of the door, comprising a two part shaft, a sliding pinion on one part, a spring, a wedge, a rocking lever and press pins controlling the locking lever and a toothed stop adapted to mesh with the sliding pinion.

6. In a device of the class specified the 130 combination of a door check adapted to

hold the door in any position with a latch operating mechanism adapted to operate the door check and a latch locking mechanism adapted to lock the latch on one side of the door and means to release the latch from the locked side of the door.

7. In a device of the class specified the combination of a door check having a latch operating mechanism adapted to operate the door check with a latch locking mechanism adapted to lock the latch on one side of the door and means to release the latch from the locked side of the door comprising a metal tape secured at one end to the side of the latch bolt, having a key grip at the other end outside a slot in the casing, and a key to enter the key grip.

8. In a device of the class specified the combination of a casing, a latch mechanism comprising a reversible latch bolt, a latch bar with spring compression coupled thereto, a rack on the lower edge of the bar, a handle controlled shaft journaled in the casing carrying a pinion meshing with the rack, an inclined slot in the latch bar a block reciprocating therein, a pin secured to the block extending outwardly through a vertical slot in the casing and door, with a rod slotted to receive the projecting pin, guides to retain the rod parallel to the door, a foot piece reciprocating in a bracket, secured to the lower end of the rod, and a resilient tip to the footpiece.

9. In a device of the class specified the com-

bination of a casing, a latch mechanism comprising a reversible latch bolt, a latch bar with spring compression coupled thereto, a rack on the lower edge of the bar, a handle controlled shaft journaled in the casing carrying a pinion meshing with the rack, an inclined slot in the latch bar a block reciprocating therein, a pin secured to the block extending outwardly through a vertical slot in the casing and door, with a rod slotted to receive the projecting pin, guides to retain the rod parallel to door, a foot piece reciprocating in a bracket, secured to the lower end of the rod, and a resilient tip to the footpiece, with means to lower the door check below the normal floor level.

10. In a device of the class specified the combination of a casing, a latch mechanism comprising a reversible latch bolt, a latch bar with spring compression coupled thereto, a rack on the lower edge of the bar, a handle controlled shaft journaled in the casing carrying a pinion meshing with the rack, an inclined slot in the latch bar a block reciprocating therein, a pin secured to the block extending outwardly through a vertical slot in the casing and door, guides to retain the rod parallel to door, a foot piece reciprocating in a bracket, secured to the lower end of the rod and an offset to the footpiece to avoid the saddle of the door.

Montreal, 22nd December, 1924.

BENJAMIN F. PERRY.
